V. HOVANEC

TOY BOWLING ALLEY

Filed Nov. 9, 1922

UNITED STATES PATENT OFFICE.

VALENT HOVANEC, OF AMBRIDGE, PENNSYLVANIA.

TOY BOWLING ALLEY.

Application filed November 9, 1922. Serial No. 599,844.

To all whom it may concern:

Be it known that I, VALENT HOVANEC, a citizen of the United States of America, residing at Ambridge, in the county of Beaver and State of Pennsylvania, have invented certain new and useful Improvements in Toy Bowling Alleys, of which the following is a specification.

This invention relates to certain new and useful improvements in toy bowling alleys wherein a frame provided with a central alley portion and longitudinally extending lateral gutters has a manually operable manikin disposed at one end thereof for throwing a ball down the alley in the direction of pins placed at the lower end thereof.

The primary object of the invention is to provide a toy bowling alley wherein a manikin that is mounted upon a vertical pivot adjacent one end of the alley is provided with a hinged arm having a socket portion at the outer end or hand thereof for holding a ball with manually operable means for swinging the arm to throw the ball down the alley.

Another object of the invention is to provide a toy bowling alley wherein a metallic blank is bent to provide guide supporting bars with a central alley portion with a depressed gutter at each side of the alley.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a perspective view of a toy bowling alley constructed in accordance with the present invention showing the pins placed at one end of the alley and a manikin having a swinging arm carrying a bowling ball disposed at the other end thereof,

Figure 2 is a detail sectional view showing the operating mechanism for the swinging arm of the manikin,

Figure 3 is a detail sectional view showing the connection between the swinging arm of the manikin and the operating mechanism therefor, and the vertical pivot for the manikin, and

Figure 4 is a perspective view of the ten-

sioned lever for operating the swinging arm of the manikin.

Referring more in detail to the accompanying drawing, the alley portion of the device is struck from a sheet metal blank 60 bent to provide side supporting bars 1 and a central longitudinal alley 2, one end of the alley being upwardly bent to provide a flange 3 adjacent the ends 4 mounted on the alley 2 in the usual arrangement. Each side 65 of the alley 2 adjacent the side supporting bars 1 is longitudinally depressed to provide gutters 5 to guide the bowling balls when the same leave the alley 2. The opposite end of the alley 2 has a pair of transversely 70 alined struck out portions defining depending ears 6, a pair of slotted openings 7 being located forwardly of the depending ears 6 while circular apertures 8 are formed in the 75 alley forwardly of the slotted openings 7, a rectangular opening 9 being formed in the extreme inner end of the alley 2 as clearly shown in Fig. 1.

The manikin 10 is positioned on the alley 2 upon the vertical pivot pin 11 that is 80 freely mounted in either of the openings 8, the manikin carrying a swinging arm 12 having a socket 13 formed at the hand portion thereof.

The operating mechanism for swinging 85 the arm 12 includes a lever that is struck out from a blank of sheet metal and bent to provide side arms 14 having transversely alined openings 15 therein that receive the pivot pin 16 knotted in the depending ears 6 carried by the alley 2. The rear ends of the lever arms 14 carry an integral upwardly directed presser head 17 that normally projects upwardly through the opening 9 in the rear end of the alley, a cross brace 18' 90 extending between the lever arms 14 outwardly of the pivot pin 16 maintaining proper relative positions of the two lever arms 14. The forward ends of the lever arms 14 are slotted as at 18 through 95 which the lower angle end 19 of a link 20 freely extends, the upper end of the link projecting through either of the slotted openings 7 in the alley 2 and being angularly bent as at 21 for free mounting in the 100 openings 22 adjacent the lower end of the swinging arm 12. The arm 12 is maintained at its limit of downward movement with the presser head 17 projecting upwardly 105 through the opening 9 in the alley 2 by the 110

coil spring 23 interposed between the lower face of the alley 2 and the cross brace 18 as clearly shown in Figs. 2 and 3.

In the operation of the device, a ball 24 is positioned in the socket 13 of the arm 12, and upon operating the presser head 17 in a downward direction, the lever arms 14 vertically shift the link 20 for swinging the arm 12 to the dotted line position shown in Fig. 2, throwing the ball 24 from the socket 13 along the alley 2 for spilling the pins 4, the spring 23 returning the swinging arm 12 to its set position and also elevating the presser head 17. By the provision of the vertical pivot pin 11 for the manikin 10, and the slot connection between the lower angle end 19 of the link 20 and the lever arm 14, the manikin 10 may be slightly rotated in either direction to control the direction of travel of the ball 24. Also, by the provision of the T-slotted opening 7 and the apertures 8 in the alley 2, the manikin 10 may be shifted from one side of the alley to the other in which either the right or left arm of the manikin may be pivotally mounted for throwing the ball 24.

While there is herein shown and described the preferred embodiment of the present invention, it is nevertheless to be understood that minor changes may be made therein without departing from the spirit and scope thereof as claimed.

What is claimed as new is:—

1. In a toy bowling alley, a metallic frame bent to provide a central alley portion and depressed to provide lateral gutters, a manikin mounted upon a vertical pivot adjacent one end of the alley and having a swinging arm for supporting a bowling ball, means for swinging the manikin arm, said means including a lever frame embodying side arms, struck out portions from the alley forming depending ears to which the arms are pivoted, said alley having a series of openings formed therein, a presser head carried by the lever arms projecting upwardly through one of said openings, and a link connection between the forward end of said arms and the swinging arm of the manikin

freely extending through one of the alley openings.

2. In a toy bowling alley, a metallic frame bent to provide a central alley portion and depressed to provide lateral gutters, a manikin mounted upon a vertical pivot adjacent one end of the alley and having a swinging arm for supporting a bowling ball, means for swinging the manikin arm, said means including a lever frame embodying side arms, struck out portions from the alley forming depending ears to which the arms are pivoted, said alley having a series of openings formed therein, a presser head carried by the lever arms projecting upwardly through one of said openings, a link connection between the forward end of said arms and the swinging arm of the manikin freely extending through one of the alley openings, a cross brace extending between the lever arms, and a coil spring interposed between the bottom face of the alley and the cross brace.

3. In a toy bowling alley, a metallic frame bent to provide a central alley portion and depressed to provide lateral gutters, a manikin mounted upon a vertical pivot adjacent one end of the alley and having a swinging arm for supporting a bowling ball, means for swinging the manikin arm, said means including a lever frame embodying side arms, struck out portions from the alley forming depending ears to which the arms are pivoted, said alley having a series of openings formed therein, a presser head carried by the lever arms projecting upwardly through one of said openings, a link connection between the forward end of said arms and the swinging arm of the manikin freely extending through one of the alley openings, the connection between the link and lever arms including an angle arm carried by the lower end of said links and slotted openings formed in the forward ends of said lever arms to which the angle end of the links freely extend.

In testimony whereof I affix my signature.

VALENT HOVANEC.
